Attorney

UNITED STATES PATENT OFFICE.

THOMAS L. KERR, OF BIGHEART, OKLAHOMA, ASSIGNOR OF ONE-HALF TO KORK KELLEY, OF DALLAS, TEXAS.

METHOD OF BLENDING GASOLINE.

Application filed May 25, 1921. Serial No. 472,326.

To all whom it may concern:

Be it known that I, THOMAS L. KERR, a citizen of the United States, residing at Bigheart, in the county of Osage and State 5 of Oklahoma, have invented certain new and useful Improvements in Methods of Blending Gasoline; and I do hereby declare the following to be a full, clear, and exact description of the invention, such as will enable others skilled in the art to which it 10 pertains to make and use the same.

The object of the invention primarily is to provide a commercial gasoline or fuel for explosion engines under conditions and a 15 method involving less complication and more stable resultant product than by the methods heretofore in use and which existing methods involve more or less essentially the mixing together of casing head gasoline and 20 an oil of greater specific gravity such as naphtha, kerosene or the like, and one of the principal objections to the present methods resides in the fact that the product is subject to stratification or lacks stability or 25 permanence of composition.

The casing head gasoline is too high or light in gravity, running usually about eighty-five per cent Baumé for practical use, owing to its high coefficient of volatility and 30 low boiling point, and consequently the difficulty of handling the same without great waste, and it is therefore necessary for practical purposes to reduce the grade on the Baumé scale as to gravity to approximately 35 seventy degrees and to raise the boiling point, and to accomplish this object I proceed as follows:

Essentially the invention consists in 40 jointly distilling the liquids of different specific gravities either in relative proportions or of relative specific gravities necessary to produce the desired combination, and combining the vapors thereof and then mutually condensing the vapors. In other 45 words the method consists essentially in combining the constituents of the product while in a vaporous condition and then condensing them in one operation.

For this purpose I use gasoline of the 50 grade usually termed casing head gasoline, just as it comes from the well and place the same and the blending agency such as kerosene in different stills with the outlets there-

of so connected as to blend the vapors discharged therefrom, and then recondense the 55 blended vapors by any suitable means, such as that indicated in the accompanying drawing illustrating a typical form of apparatus, wherein the gasoline still is indicated at 10, the still for blending agency at 11, the mixing chamber at 12 and the condensing coil at 13, and the receiving tank at 14.

I have found in practice that in the distillation of the kerosene or like material used as a blending agency the lighter hydro-carbons or those of less specific gravity go over first as obviously is natural and therefore in order to maintain the uniform or homogeneous character of the product I preferably duplicate still 11, and after the lighter 65 hydro-carbons have been carried over from the still 11 I draw the residue from that still into the still 11^a where I subject it to a higher temperature, continuing this operation to effect a combination or blending of 70 the vapors of all three densities in the mixing chamber. In the same way the blended vapors of relatively different densities are 75 condensed in one operation.

By following this procedure in essential 80 features it is possible to produce practically any grade or specific gravity of the product and to vary the boiling point as may be required and consequently the proof or ignition point to insure any required degree 85 of safety, and have found in practice that there is no tendency whatsoever for the product thus produced to stratify as is the case where the combination is effected by blending the liquids or blending the ingredients 90 while in a liquid form.

While in the foregoing description and also for convenience in the claims hereto appended the terms used have specifically included gasoline, kerosene and the like, it 95 should be understood that by the former is meant any high grade, low proof and highly volatile fuel or product which it may be desired to blend down or reduce in volatility, while the second applies to and includes 100 any appropriate product or oil of relatively low grade and high proof of less volatility or lower coefficient of volatility which in the blend will serve to neutralize or modify or lower the standard or grade of volatility of 105 the product and thereby raise the proof

thereof for reasons of safety in handling with the consequent reduction of risk in that connection.

Having thus described the invention, what

5 I claim is:—

1. A method of producing a commercial gasoline which consists in vaporizing casing head gasoline, vaporizing kerosene of a lower specific gravity, combining the vapors

10 of the gasoline and kerosene and finally condensing the blended vapors.

2. The method of producing a hydrocarbon oil consisting in commingling the separate vapors of casinghead gasoline and

15 vapors from a product of petroleum oil, and condensing said vapors to a liquid state.

3. The method of making a hydrocarbon

oil which includes distilling casing head gasoline, distilling a heavier hydrocarbon oil, commingling their vapors, and condensing 20 the commingled vapors.

4. The method of making hydrocarbon oil which includes boiling a hydrocarbon oil of greater volatility than commercial gasoline, boiling a heavier hydrocarbon oil, commingling 25 their vapors, and condensing the commingled vapors.

In testimony whereof I affix my signature in presence of two witnesses.

THOMAS L. KERR.
